UNITED STATES PATENT OFFICE.

HARRY F. JOHANINGMYER, OF ST. LOUIS, MISSOURI, ASSIGNOR TO FRANK ADAM ELECTRIC COMPANY, OF ST. LOUIS, MISSOURI, A CORPORATION OF MISSOURI.

KNIFE-SWITCH.

1,235,693.

Specification of Letters Patent.

Patented Aug. 7, 1917.

Application filed April 21, 1916. Serial No. 92,709.

To all whom it may concern:

Be it known that I, HARRY F. JOHANINGMYER, a citizen of the United States, residing at St. Louis, Missouri, have invented a 5 certain new and useful Improvement in Knife-Switches, of which the following is a full, clear, and exact description, such as will enable others skilled in the art to which it appertains to make and use the same.

10 This invention relates to knife switches, and particularly to the means used in such structures for pivotally connecting the blade to the hinge standard of the switch.

When an ordinary bolt and nut are used 15 for connecting the blade of a knife switch to the hinge standard, a great deal of care on the part of the workman is required in adjusting the nut on the bolt, so that the blade will have the proper frictional contact with the hinge standard and still be 20 able to swing freely. An ordinary nut and bolt also necessitates the use of a lock nut or jam nut to prevent the clamping nut on the bolt from working loose. And still another 25 objectionable feature of such a structure is that it is not symmetrical, the head of the bolt which is positioned on one side of the standard presenting a different appearance than the clamping nut or the 30 clamping nut and jam nut positioned on the other side of the standard on the exposed end portion of the bolt.

The main object of my invention is to 35 provide a knife switch which is so constructed that the blade and hinge standard can be assembled properly without accurately adjusting the clamping means that joins said parts together, thus enabling the switch to be manufactured at a low cost, on 40 account of the saving in time and the fact that low-priced labor or a nut-tightening machine can be used in the assembling operation.

Another object is to provide a knife switch 45 in which the means that connects the blade to the hinge standard is symmetrical and presents the same appearance on both sides of the hinge standard.

And still another object is to provide a 50 blade mounting for knife switches which makes it commercially possible to produce knife switches that are uniform so far as the mounting of the blade is concerned.

Figure 1 of the drawings is a side eleva-

tional view of a knife switch constructed in accordance with my invention.

Fig. 2 is a horizontal sectional view, taken on the line 2—2 of Fig. 1.

Fig. 3 is a horizontal sectional view similar to Fig. 2, illustrating a slight modification of my invention; and

Fig. 4 is a perspective view of the means used in the switch shown in Fig. 1 for connecting the blade to the hinge standard of the switch.

Referring to Figs. 1 and 2 of the drawings, which illustrate one form of my invention, A designates the blade of a knife switch, and B designates the hinge standard to which said blade is pivotally connected, 70 the standard B herein shown consisting of a bifurcated member whose two side parts or legs 1 embrace the blade A, as shown in Fig. 2. Said blade and standard are pivotally connected together by means of a device that comprises a cylindrical-shaped body portion provided at its opposite ends with heads or cap pieces 2 that lap over 75 spring washers 3 which bear against the opposite side faces of the hinge standard B. 80 The cylindrical-shaped body portion of said device passes through aligned holes in the blade A and in the two side pieces 1 of the standard that embrace said blade, and in the form of my invention shown in Fig. 2, 85 said body portion is composed of two sections *x* and *y* that are detachably connected together, the head or cap pieces 2 at one end of the device being integrally connected to the section *x*, and the head or cap pieces 90 2 at the other end of the device being integrally connected to the section *y*. The section *x* of the body portion of the connecting device is provided with an internally screw-threaded socket 4, as shown in Fig. 2, and 95 the section *y* of said body portion is provided with an externally screw-threaded extension or reduced portion 5 that is screwed into said socket 4, said sections being provided at their meeting ends with shoulders 100 that abut against each other when said sections are screwed together.

With a connecting device of the construction above described it is not necessary to accurately adjust same during the operation of assembling the blade and the standard of the switch on account of the fact that the length of the body portion of the device

will always be the same when the two sections constituting said body portion are screwed tightly together. In other words, the space between the two heads or cap pieces 2 of the device that lap over the spring washers 3 is fixed, and therefore, in assembling the standard and blade of the switch all that the workman has to do is to screw the section *y* into the section *x* until the coöperating shoulders of the meeting ends of said sections abut tightly against each other. The spring washers 3 have sufficient resiliency to compensate for any slight variation in the thickness of the blade 15 *A* or in the two side parts 1 of the hinge standard, and therefore, if the connecting devices are properly designed and are uniform, the switches will be uniform, so far as the mounting of the blades is concerned. 20 Low-priced labor or a nut-tightening machine can be used in assembling the blade and hinge standard of a switch of the construction above described, as it is not necessary to adjust the connecting device accurately in tightening same, and as the two sections *x* and *y* of the body portion of the connecting device can be set up tightly or screwed tightly together, there is little liability of their working loose, thus overcoming 25 the necessity of using a locking device, as is necessary when an ordinary bolt and nut are used to connect the blade of a knife switch to the hinge standard. In addition to the desirable features above pointed out, 30 a knife switch of the construction above described presents a neat and ornamental appearance, as the exposed portions of the connecting device that are arranged on opposite sides of the hinge standard are symmetrical. 35 It is immaterial, so far as my broad idea is concerned, how the body portion of the connecting device is formed, so long as it is of such design that the connecting device can be arranged in operative position with- 40 out carefully adjusting same so as to cause the blade to have the proper frictional engagement with the standard and still be capable of swinging easily. In Fig. 3 I have illustrated a slight modification of my 45 invention in which the body portion of the device is composed of three sections, two end sections *x'* and *y'* and an intermediate 50

section *z* that is detachably connected to said end sections and which is provided at its opposite ends with shoulders or bearing 55 surfaces that abut tightly against coöperating shoulders or bearing surfaces at the inner ends of the end sections *x'* and *y'* when said end sections are screwed into the intermediate section *z*, said intermediate section being preferably in the form of a sleeve 60 having internal screw threads that receive externally screw-threaded projections 6 on said end sections *x'* and *y'*. The connecting device illustrated in Fig. 3 is particularly 65 designed for use in a switch provided with a plurality of blades *A'*, and one desirable feature of same is that it can be modified easily to adapt it to switches having different numbers of blades by simply substituting 70 an intermediate section *z* of the proper length.

Having thus described my invention, what I claim, and desire to secure by Letters Patent, is:

1. In a knife switch, the combination of a blade, a hinge standard, and a connecting device passing through said parts for pivotally connecting them together and comprising separable clamping elements connected together by coöperating screw threads and provided with portions that butt tightly against each other and thus hold said clamping elements spaced apart a definite distance during the operation of assembling the 85 structure.

2. In a knife switch, the combination of a blade, a bifurcated standard that straddles said blade, a pivotal connecting device passing through said elements and provided with cap pieces or heads arranged at the opposite ends of same and a separable body portion that holds said cap pieces spaced apart a definite distance, and spring washers interposed between said cap pieces and the outside 95 faces of said standard.

In testimony whereof I hereunto affix my signature, in the presence of two witnesses, this nineteenth day of April, 1916.

HARRY F. JOHANINGMYER.

Witnesses:

WELLS L. CHURCH,
GEORGE BAKEWELL.
